GEORGE F. SILKNITTER, OF SIOUX CITY, IOWA

SAMPLING DEVICE

Application filed April 14, 1930. Serial No. 444,322.

My invention relates to the securing of samples of oils and greases such as those that are used in the making of soaps, for the purpose of testing and sampling of such products.

It will be understood that the process in an ordinary rendering plant of storing greases is to run the hot greases and oils from the rendering vats into a series of tanks or drums of large capacity.

The amount of greases and oils piped into a tank at one time will ordinarily be sufficient to fill only a small portion of the drum. The grease will form a layer and harden and the next batch that is piped in will form another layer upon the previously formed layer.

The successive layers of greases and oils will vary according to the nature and quality of the particular batch of grease. Thus there will be produced in each tank a succession of layers of greases and oils of varying quality.

When a tank of grease is sold by a rendering plant to a soap manufacturing company or to any concern which uses rendered fats, the purchaser requires a test to be made of the contents of the tank. This is ordinarily accomplished by opening a series of petcocks disposed at varying levels in the tank, heating the grease within the tank and allowing a portion of the contents to flow from each petcock. The heating process is necessary in order to render the grease fluid enough so that it will flow from the petcocks. This heating operation takes considerable time and is quite expensive since a large proportion of the contents of the tank must be heated in order to obtain drainage from the petcocks.

My invention has for its object to provide a device adapted to secure a sample of the contents of a tank in a minimum period of time with a minimum amount of difficulty.

Another object of my invention is to provide a device which will procure a sample of the grease, obtaining equal quantities from each level in the tank. In this connection it may be said that the present process is very inaccurate because of the difficulty of obtaining the same flow from each petcock.

A further object of my invention is to provide a device which will secure a sample of the entire cross sectional depth of the tank. The present method will not do this because of the impracticability of placing petcocks close enough together to produce the result.

Another object of my invention is to provide a device which will not injure the greases in the heating process.

With these and other objects in view, my invention consists in the construction, arrangement and combination of the various parts of my device, whereby the objects contemplated are attained, as hereinafter more fully set forth, pointed out in my claims, and illustrated in the accompanying drawing, in which:

Fig. 1 is a sectional view through the sampling mechanism.

Fig. 2 is a sectional view through the sampling mechanism.

Fig. 3 is a side elevation of the upper portion thereof and

Fig. 4 is a transverse, sectional view through the sampling mechanism.

In the accompanying drawing, an ordinary grease storage tank or drum is shown at 10, the top wall 11 thereof being provided with an opening 12, which is closed by a hinge cover 13. The various levels of greases are indicated roughly at 14 in Fig. 1. My invention is comprised in a permanent installation including a casing 15, closed at its lower end as by means of a cap 16 and suitably supported in some manner within the tank 10 as by means of a base plate 17, attached to the cap 16 or forming part thereof and riveted or bolted to the bottom wall of the tank 10. It will be understood that any means for supporting the casing 15 in an upright position within the tank might be employed.

The parts which remain permanently within the tank are shown in Fig. 3 and connections are adapted to be made to these parts from the outside as shown in Fig. 1 when the sampling process is to be carried out.

Within the casing 15, which is cylindrical, being preferably constructed of piping or tubing of diameter ranging from three inches

upwardly, is a cylindrical sleeve 18 of smaller tubing fitting snugly within the casing 15.

The sleeve 18 is rotatable within the casing 15 and is provided at its upper end with a handle 19, by means of which it may be rotated.

10 A finger 20 is secured to the sleeve 18 and projects over the edge of the casing 15 to engage a lug 21 on the casing 15. The finger 20 may be formed on a ring 22 by means of which the handle 19 is secured to the sleeve 18.

15 The casing 15 and sleeve 18 are provided each with a series of spaced holes, one of which is numbered 23 and the other 24. The holes 23 and 24 are adapted to register when the finger 20 is in contact with the lug 21.

20 A steam coil 25 extends into the space within the sleeve 18 and the ends 26 and 27 thereof are provided with suitable connections 28 for attachment to steam lines 29 and 30 as shown in Fig. 1. The steam lines 29 and 30 include valves 31 for controlling the flow of steam to the coil 25.

25 A pipe 32 is extended into the space within the sleeve 18 that is not occupied by the coil 25. Various methods of arranging the coil 25 and pipe 32 might be employed although the simplest is to provide the coil 25 in the form of two parallel lengths of tubing connected at their lower ends by an elbow 33, the pipe 32 being disposed centrally between the two lengths of tubing of the coil 25.

30 The pipe 32 is terminated at a distance 35 from the bottom of the cap 16 so that grease may flow into the lower end of the pipe.

The upper end of the pipe 32 is provided with a connection 36 to which may be attached a tube 37 leading to a suction pump.

40 The pump is not shown but any conventional design of suction pump adapted to lift the melted grease from the sleeve 18 may be employed.

45 In operation, the device functions as follows: The handle 19 is left normally in a position where the openings 23 and 24 register, whereby as the grease is delivered into the tank 10 from the rendering plant it may fill the sleeve 18 to substantially the same level 50 as in the tank. Successive layers of grease will thus settle and harden within the sleeve 18 and when the tank is full and it is desired to sample the grease, the door 13 is opened, the steam pipes 29 and 30 are attached to the 55 coil 25 and steam is allowed to flow through the coil until the grease within the sleeve 18 has been brought to a fluid state. Thus it is not necessary to heat the grease within the tank.

60 Before the grease is to be pumped out of the sleeve 18, the handle 19 is moved to a position wherein the openings 23 and 24 are out of register. This will seal the casing against the inflow of any grease which may have been 65 come melted around the outer side of the cas-

ing and only the grease standing within the sleeve 18 may be pumped out.

70 Thus a true cross section of the contents of the tank is obtained in the sample which is pumped out. The pipe 37 is attached to the pipe 32 preliminary to the pumping operation; the contents are pumped from the sleeve 18; the pump is then detached and the steam lines and the door 13 may then be again closed.

75 An alternate method of operation is to leave the casing closed against the inflow of grease until it is desired to sample the contents of the tank and to then heat the grease surrounding the casing by means of the steam coil 25, the heating process being carried out until a sufficient quantity of grease has been melted to insure the filling of the sleeve 18. The handle 19 may then be turned to open the casing and allow the grease to flow into the sleeve.

80 It will be seen that my invention provides a permanent installation which does not interfere with the opening and closing of the door 13. Furthermore my invention makes it possible to employ steam heat for heating the contents of the tank.

85 A primary advantage residing in my invention is in the uniform sampling which is obtained by allowing the fluid grease to 90 flow into the sampling device through a series of very closely spaced openings whereby a true cross section of contents is obtained. An equally important advantage of my invention resides in the rapidity with which the sampling may be done where only a small portion of the grease need be melted and wherein means for uniformly and simultaneously heating this small portion from top to bottom of the tank is provided.

95 Another important advantage of my invention resides in the fact that the grease has to flow only through the two thin walls of a pair of tubes a much shorter distance than it is required to flow through a petcock.

100 The time which is required in order to obtain a sample by means of my invention is only a fraction of that required by former methods.

105 I claim as my invention:

110 1. In combination with a grease storage tank having an opening in its upper wall normally closed by a cover, a sampling device comprising a tubular casing secured within the tank in an upstanding position with its upper end nearer the said opening, a plurality of openings in the wall of the casing in vertically spaced succession, means for opening and closing said openings, a pipe 115 communicating with the space within the casing at the lower extremity thereof for pumping off the contents of the casing and a steam coil arranged in conjunction with the casing, the upper ends of the coil and pipe being positioned near said opening and adapted 120

125

130

to be attached to steam pipes and a pumping tube, respectively, extended through said tank opening.

2. In combination with a grease storage tank having an opening in its upper wall normally closed by a cover, a sampling device comprising a tubular casing secured within the tank in an upstanding position with its upper end near the said opening, a plurality of openings in the wall of the casing in vertically spaced succession, means for opening and closing said openings, a pipe communicating with the space within the casing at the lower extremity thereof for pumping off the contents of the casing, the upper end of the pipe being positioned near said opening and adapted to be attached to a pumping tube extended through said opening.

3. In combination with a grease storage tank having an opening in its upper wall normally closed by a cover, a sampling device comprising a tubular casing secured within the tank in an upstanding position with its upper end near the said opening, a plurality of openings in the wall of the casing in vertically spaced succession, means for opening and closing said openings, a steam coil arranged in conjunction with the casing, the upper ends thereof being positioned near said opening and adapted to be attached to steam pipes extending through said opening.

4. In combination with a grease storage tank having an opening in its upper wall normally closed by a cover, a sampling device comprising a tubular casing secured within the tank in an upstanding position with its upper end near the said opening, a plurality of openings in the wall of the casing in vertically spaced succession, means for opening and closing said openings, a steam coil arranged in conjunction with the casing, the upper ends thereof being positioned near said opening, steam pipes extending above said tank near said opening, and detachable connections between the steam pipe and the steam coil, extending through said opening.

Signed this 3rd day of April, 1930, in the county of Woodbury and State of Iowa.

GEORGE F. SILKNITTER.
